UNITED STATES PATENT OFFICE.

ARTHUR L. CLEAVER, OF NEW YORK, N. Y.

DESIGN FOR A FISHING-ROD TIP.

SPECIFICATION forming part of Design No. 32,653, dated May 15, 1900.

Application filed April 21, 1900. Serial No. 13,815. Term of patent 14 years.

To all whom it may concern:

Be it known that I, ARTHUR L. CLEAVER, a citizen of the United States, residing at the city of New York, borough of Manhattan, in the county of New York and State of New York, have invented and produced a new and original Design for a Fishing-Rod Tip, of which the following is a full, clear, and exact description.

Reference is to be had to the accompanying drawings, forming a part of this specification, in which similar characters of reference indicate corresponding parts in all the views.

Figure 1 is a perspective view of a fishing-rod tip, showing my design. Fig. 2 is a transverse section of the same on the line 2-2 in Fig. 3, and Fig. 3 is a longitudinal section of the same.

The design in its entirety consists of a cylindrical shank A, appearing with a recess B at one end and with a head C at the other

end, the head having depending parallel flanges D and an arch-shaped top portion E, a half-round groove F appearing under the top portion E and between the flanges, terminating at the rear thereof at the under side of the shank A, as plainly shown in Fig. 3.

The leading feature of the design consists of a shank having a head appearing with the flanges and groove.

Having thus fully described my invention, I claim as new and desire to secure by Letters Patent—

The design for a fishing-rod tip, as herein shown and described.

In testimony whereof I have hereunto signed my name to this specification in the presence of two subscribing witnesses.

ARTHUR L. CLEAVER.
